PAPER SHEET

Lee B. Kuhn, Brooklyn, N. Y.

Application June 24, 1933, Serial No. 677,384

1 Claim. (Cl. 281—43)

My invention relates to sheet papers, such, for example, as that used in stationery, menu cards and the like, and in particular it is directed to a sheet which facilitates the use of such paper for advertising matter without detracting from its appearance or usefulness.

Advertising matter is frequently printed on stationery but in general such advertising matter detracts from the appearance of the stationery and also from the usefulness thereof as it generally occupies a good portion of the stationery. It is, however, desirable to utilize stationery for advertising purposes as many business houses write numerous letters with which it is frequently 10 desirable to distribute advertising matter describing some specialty. Commonly, stickers containing the advertising matter are secured to the letter or, in the case of public service companies, to the bills which are distributed. These stickers are 15 annoying and detract from the dignity of the stationery or other similar sheet and the advertising matter, and it is an object of my invention to provide a paper sheet which may be used for bills, stationery, menu cards or the like and which 20 may carry advertising matter that is set off and does not detract from the appearance or usefulness of the sheet to which it is attached.

A paper sheet embodying my invention includes two portions, a body portion for the use for 25 which the sheet is particularly adapted, such as the writing, in the case of stationery; or the menu, in the case of a menu card, and an extended portion extending from an edge of the body portion. This extended portion is of less 30 width than the sheet and is foldable to a position within the perimeter, and against the body portion of the sheet along the line of juncture between the extended portion and the body portion. The extended portion is adapted to carry 35 the printed advertising matter. On the body portion of the sheet there is a lip positioned to receive the free edge of the extended portion and thus hold this edge in contact with the body portion and the entire extended portion within the 40 perimeter of the body portion.

A specific form of my invention includes a sheet 45 with an extended portion having a shaped section constituting a substantial portion of its outer edge. The extended portion is folded at the base 50 of the shaped section so that it has a free, folded edge. At a distance from the edge of the body portion, to which the extended portion is attached, equal to slightly less than the distance between 55 the edge of the body portion of the sheet and the free folded edge of the extended portion, there is

a lip on the body portion of the sheet. This lip receives the free, folded edge of the body portion and because of the shorter distance of the lip from the edge of the body portion than the folded, free edge of the extended portion, the extended 60 portion which folds in a direction to lie against the body portion is slightly bulged when the folded edge is received behind the lip. This bulge is directly behind the shaped section of the extended portion and causes that portion to raise from 65 the surface of the sheet when pressure on it is relieved, thus setting off this shaped portion in relief. The shaped portion also forms a tab by which the extended portion may be withdrawn from behind the tongue and thus expose to view 70 the advertising matter printed on the under-side of the extended portion connected with the shaped section.

A clearer understanding of my invention will be had from the following particular description of the embodiment thereof shown in the accompanying drawing, in which:

Fig. 1 is a plan of a sheet embodying my invention as it would appear in use;

Fig. 2 is a plan with the extended portion 80 of the sheet withdrawn from behind the lip; and

Fig. 3 is a section taken on the line 2—2 of Fig. 1.

While I have illustrated my invention as it would be used in connection with business stationery, it is of course obvious that the particular use to which the sheet is put is of no importance and is not restrictive in so far as my invention is concerned. The sheet shown in the drawing includes a body portion 1 similar 85 to the usual business stationery. This body portion is for the communication which may be written thereon. A portion of less width than the body portion extends from the upper or top edge of the body portion. This extended portion 90 is integral with the body portion 1 and is foldable along the line of juncture with the body portion, that is, along the upper edge of the body portion.

As illustrated, the extended portion includes 100 an outer shaped section 2a and a connecting section 2b extending from the base of the shaped section to the edge of the body portion of the sheet. The shaped section is die-cut, in this instance it represents the lines of an automobile. 105 The particular character of the shaped section will of course be harmonized with the advertising. At the base of this shaped section, the extended portion is folded as shown, dividing the extended portion into the two sections men- 110

tioned. This folding of the shaped section at the base thereof leaves a free, folded edge 2c on the extended portion.

A lip 1a is cut in the body portion of the sheet.

- 5 The base of the cut forming this lip and consequently the base of the lip is positioned from the edge of the body portion, from which the extended portion is attached, a distance slightly less than the distance between the edge of the body portion and the free, folded edge of the extended portion, i. e. slightly less than the length of the connecting section of the extended portion. The free, folded edge of the extended portion is adapted to be received behind this lip.
- 10 When so received the free, folded edge abuts against the base of the lip and causes the section 2b of the extended portion to bulge. When there is no pressure on the sheet this section of the extended portion bulges and causes the shaped section 2a of the extended portion to stand up from the plane of the paper and it is set off in relief, making a very effective advertisement. The upstanding, shaped section also constitutes a tab by which the extended portion of the sheet
- 15 can be withdrawn from behind the lip and unfolded, exposing on the under-side the printed advertising matter as illustrated in Fig. 2. Various flaps can of course be arranged on the extended portion of the sheet to provide additional
- 20 area for advertising matter.

The extended section may be perforated along the fold and also along the junction with the body portion as indicated by broken lines. Thus the advertising matter may be readily detached from the body of the sheet.

It is obvious that various changes may be made by those skilled in the art in the details of the embodiment of my invention as illustrated in the drawing and above particularly described within the principle and scope of my invention as expressed in the appended claim.

I claim:

A paper sheet comprising a body portion for the particular use for which the paper is adapted and a portion of lesser width extending from one edge of said body portion and foldable along the line of juncture between the extended portion and the body portion, said extended portion having a shaped section at the free edge thereof and being folded at the base of the shaped section, and a lip on the body portion of the sheet positioned from the edge thereof a distance equal to slightly less than the distance between the edge of the body portion and the folded free edge of the extended portion, said lip being adapted to receive the folded free edge of the extended portion.
